UNITED STATES PATENT OFFICE.

WILLIAM C. HORNER, OF INDIANAPOLIS, INDIANA, ASSIGNOR TO
CHARLES P. McDougall, OF INDIANAPOLIS, INDIANA.

KITCHEN-CABINET.

No. 824,865.

Specification of Letters Patent.

Patented July 3, 1906.

Application filed October 7, 1905. Serial No. 281,852.

To all whom it may concern:

Be it known that I, WILLIAM C. HORNER, a citizen of the United States, residing at Indianapolis, in the county of Marion and State 5 of Indiana, have invented certain new and useful Improvements in Kitchen-Cabinets, of which the following is a specification.

The object of my invention is to provide a cabinet having a closet-space and an adjacent drawer having an open vertical face, the arrangement being such that said drawer may be withdrawn horizontally from the casing, and also such that the contents thereof will be accessible from the closet-space with- 15 out withdrawing the drawer from the cabinet.

The accompanying drawings illustrate my invention.

Figure 1 is a perspective view showing the vertical drawer partially withdrawn from the cabinet, and Fig. 2 is a vertical section showing the relation of said vertical drawer to the other portions of the cabinet.

In the drawings, 10 indicates a suitable cabinet or casing within which is slidably mounted the vertical drawer 11, said vertical drawer being provided with one or more horizontal shelves 12, which extend from the front 11' to the rear 11''. The drawer 11 has at least one of its vertical faces open, 25 and in order to prevent accidental lateral displacement of material placed upon the

shelves 12 I prefer to provide guard-rails 13 adjacent each shelf 12, extending from the front 11' to the back 11''. The vertical drawer 11 is arranged adjacent a closet-space 35 16, which is closed by any suitable means, such as a swinging door 17. The vertical drawer 11 slides in suitable guides 18, arranged within the casing; but there is no partition between the open face of the vertical drawer and the closet-space 16, thus making it possible to have access to the material carried by the vertical drawer through the closet-space and without withdrawing the drawer, if desired. Such construction is especially desirable where kitchen-space is at a premium during active operations. 45

I claim as my invention—

The combination, with a suitable inclosing casing having a closet-space, of a vertical 50 drawer slidably mounted therein and having an open vertical face arranged adjacent the said closet-space and accessible therefrom, and a closure for said closet-space.

In witness whereof I have hereunto set my 55 hand and seal, at Indianapolis, Indiana, this 27th day of September, A. D. 1905.

WILLIAM C. HORNER. [L. S.]
